US0D1048448S

(12) **United States Design Patent** (10) **Patent No.:** **US D1,048,448 S**
(45) **Date of Patent:** **** Oct. 22, 2024**

(54) **SPERM SAMPLER**

(71) Applicant: **TENGA Co., Ltd.**, Tokyo (JP)

(72) Inventor: **Yuki Iwasawa**, Tokyo (JP)

(73) Assignee: **TENGA CO., LTD.**, Tokyo (JP)

(**) Term: **15 Years**

(21) Appl. No.: **35/515,695**

(22) Filed: **Nov. 16, 2022**

(80) **Hague Agreement Data**

Int. Filing Date: **Nov. 16, 2022**

Int. Reg. No.: **DM/224955**

Int. Reg. Date: **Nov. 16, 2022**

Int. Reg. Pub. Date: **Dec. 2, 2022**

(30) **Foreign Application Priority Data**

Jun. 17, 2022 (JP) 2022-013070

(57) **CLAIM**

The ornamental design for a sperm sampler as shown and described.

DESCRIPTION

1. Sperm sampler

1.1 : Perspective

1.2 : Front

1.3 : Back

1.4 : Left

1.5 : Right

1.6 : Top

1.7 : Bottom

The broken lines shown on claimed surfaces in the reproductions depict portions of the sperm sampler that form no part of the claimed design. The broken lines on reproductions 1.1-1.5 shown separate from the claimed surfaces depict environmental structure of the sperm sampler that form no part of the claimed design.

1 Claim, 7 Drawing Sheets
